UNITED STATES PATENT OFFICE

HENRY HOJDA, OF MORAVSKA-OSTRAVA, CZECHOSLOVAKIA

PARACHUTE

Application filed June 2, 1932. Serial No. 614,943.

This invention relates to new and useful improvements in a parachute.

The invention has for an object the construction of a parachute which is characterized by a sail carrying a plurality of funnel-shaped members upon its edge arranged for directing air within the sail to inflate it.

Another object of this invention is the provision of a cup-shaped container for attachment upon the back of a person and provided at its top edge with a plurality of rings capable of co-acting with said funnel-shaped members to insure the proper directing of air within the sail.

As another of the objects of this invention, it is proposed to provide resilient means for connecting each of the funnel members with each of the rings.

Furthermore, as another object of this invention it is proposed to arrange a drum rotatively upon the bottom of said cup-shaped container and connected with ropes with the sail for the purpose of drawing the sail into its inoperative position.

As another object of this invention it is proposed to arrange rings upon the bottom of each of the funnels and to connect the cables which connect with the parachute sail with said rings.

Furthermore, as another object of this invention it is proposed to construct a device of the class mentioned which is of simple, durable construction, dependable in use and efficient in action, and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an elevational view of the parachute in use.

Fig. 2 is an enlarged fragmentary sectional view through one of the funnels on the edge of the parachute sail and looking towards the sail.

Fig. 3 is a fragmentary horizontal sectional view taken on the line 3—3 of Fig. 2.

Fig. 4 is a perspective view of the container for attachment upon one's back to which the sail is connected by cables.

Fig. 5 is a fragmentary sectional view showing one of the funnels from the parachute sail engaging one of the rings from the container.

Fig. 6 is a fragmentary horizontal sectional view taken on the line 6—6 of Fig. 5.

The parachute, according to this invention, comprises a sail 10 of customary shape and construction. A plurality of funnel-shaped members 11 are attached at spaced distances along the periphery of the sail 10. The attachment is accomplished by bosses 12 from the funnel-shaped member being formed with apertures through which bolts 13 pass. Washers 14 are located upon the outer face of the parachute sail so as to insure proper connection of the parts. On diametrically opposite sides on the bottom of the funnel rings 15 are attached through which a continuous rope 16 passes which connects with a cable 17 extending downwards to the container portion of the parachute as herein-after fully described.

The container portion comprises a cup-shaped container 18 for attachment upon one's back. For this purpose, upon one side bosses 19 protrude and support straps 20 capable of engaging over one's shoulder and across the chest to accomplish the attachment. Bottom apertures 21 are formed within the bottom of the cup-shaped container 18 for the purpose of allowing air to enter. A plurality of rings 22 are attached along the periphery of the cup 18 along diameters to project from the cup and correspond in number with the funnel-shaped members 11. These rings are adapted to support the funnel-shaped members when the parachute is in a collapsed position.

Each of the rings 22 project to the outside and to the inside of the container so that air from the outside and inside may enter the funnels. At diametrically opposite sides the ring 22 is formed with cutout portions 24 through which resilient springs 25 project.

These springs are engageable against peripheral grooves 26 formed within a shoulder portion 27 upon the bottom of the funnel 11. This shoulder portion allows the funnel to 5 properly seat on the top ring while the springs 25 engage the grooves 26 resiliently holding the parts thus connected.

The ropes 17 extend selectively through the rings 22 and then through an opening 10 28 in the bottom of the container 18. From there they extend about a drum 29 rotatively supported on lugs 30 projecting from the bottom of the container. A handle 31 is for the purpose of turning the drum to draw the 15 ropes thereon. In Fig. 1 a man 32 is shown descending with the parachute.

Normally, the parachute sail is disposed within the cup-shaped contained 18 and each of the funnel members 11 are engaged selectively upon the rings 22. When the parachute is used it is first strapped upon one's back. Then when the person jumps out from the plane into space, air will enter the openings 21 and pass through the rings 22 and 25 join with other air passing through the rings from the outside of the container and then through the funnels 11 into the parachute sail. The arrangement of the rings of the funnel insure the opening of the sail. As 30 soon as stress takes place between the sail 10 which is opening and the container 18, the funnel members 11 will be snapped out from engagement with the rings 22 in that the springs 25 will give to allow disengagement 35 of the parts. Then the parachute sail assumes an open position way up above the container as shown in Fig. 1, and the person may land safely.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention what I claim as new, and desire to secure by United States Letters Patent is:—

1. A parachute, comprising a cup-shaped 50 container for attachment upon one's back and having bottom apertures, means for attaching said container upon one's back, rings upon the periphery of said cup-shaped container and extending outwards and inwards, a parachute sail, funnels attached upon the edge of said sail and seatable selectively upon said rings, ropes attached upon said funnels and extending through said rings and through the bottom of said container, and means upon 55 the bottom of the container for storing said ropes in a wound condition to constitute the inoperative condition of the parachute.

2. A parachute, comprising a cup-shaped 60 container for attachment upon one's back and having bottom apertures, means for attaching

said container upon one's back, rings upon the periphery of said cup-shaped container and extending outwards and inwards, a parachute sail, funnels attached upon the edge of said sail and seatable selectively upon said rings, ropes attached upon said funnels and extending through said rings and through the bottom of said container, and means upon the bottom of the container for storing said ropes in a wound condition to constitute the inoperative condition of the parachute, said means for attaching the container upon one's back 70 includes straps. 75

3. A parachute, comprising a cup-shaped container for attachment upon one's back and having bottom apertures, means for attaching said container upon one's back, rings upon the periphery of said cup-shaped container and extending outwards and inwards, a parachute sail, funnels attached upon the edge of said sail and seatable selectively upon said rings, ropes attached upon said funnels and extending through said rings and through the bottom of said container, and means upon the bottom of the container for storing said ropes in a wound condition to constitute the inoperative condition of the parachute, said funnels being formed with shoulders for seating upon the rings while the reduced portions extend into them. 85 90 95

4. A parachute, comprising a cup-shaped container for attachment upon one's back and having bottom apertures, means for attaching said container upon one's back, rings upon the periphery of said cup-shaped container and extending outwards and inwards, a parachute sail, funnels attached upon the edge of said sail and seatable selectively upon said rings, ropes attached upon said funnels and extending through said rings and through the bottom of said container, and means upon the bottom of the container for storing said ropes in a wound condition to constitute the inoperative condition of the parachute, comprising a drum rotatively mounted and connected 100 105 110 with the ends of said ropes.

5. A parachute, comprising a cup-shaped container for attachment upon one's back and having bottom apertures, means for attaching said container upon one's back, rings upon the periphery of said cup-shaped container and extending outwards and inwards, a parachute sail, funnels attached upon the edge of said sail and seatable selectively upon said rings, ropes attached upon said funnels and extending through said rings and through the bottom of said container, means upon the bottom of the container for storing said ropes in a wound condition to constitute the inoperative condition of the parachute, and means for resiliently holding each of the funnels and rings together. 115 120 125

6. A parachute, comprising a cup-shaped container for attachment upon one's back and having bottom apertures, means for attaching

said container upon one's back, rings upon the periphery of said cup-shaped container and extending outwards and inwards, a parachute sail, funnels attached upon the edge of said sail and seatable selectively upon said rings, ropes attached upon said funnels and extending through said rings and through the bottom of said container, means upon the bottom of the container for storing said ropes in a wound condition to constitute the inoperative condition of the parachute, and means for resiliently holding each of the funnels and rings together, comprising springs upon the rings engageable within grooves in said funnels.

In testimony whereof I have affixed my signature.

HENRY HOJDA.
